UNITED STATES PATENT OFFICE.

ISAAC SNOW, OF LAWRENCE, MASSACHUSETTS.

SHUTTLE.

1,344,734.

Specification of Letters Patent. Patented June 29, 1920.

Application filed December 26, 1919. Serial No. 347,579.

To all whom it may concern:

Be it known that I, ISAAC SNOW, a citizen of the United States, residing at Lawrence, in the county of Essex and State of Massachusetts, have invented certain new and useful Improvements in Shuttles, of which the following is a specification.

My invention relates to an improvement in shuttles, more particularly of the self threading type for weft replenishing looms.

The object of my invention is to provide a shuttle threader of simple construction which can readily be located in a threading chamber, one in which the operation of self threading may be performed with certainty and one in which, when threaded, dethreading will be impossible or very improbable.

Other purposes of my invention are to reduce the likelihood of ballooning by the thread and the elimination of all points, beaks, or other projecting parts in any position where a loop of the thread can catch or loop around them.

For convenience and for the purpose of identification in this specification, I will call the "front," that end of the shuttle where the eye is located, and the other end of the shuttle the "back."

I will call an eye which passes out of the left side when looking at the front point, a "left eye," and an eye on the opposite side, a "right eye."

In all the figures of the drawings, I show a shuttle with a left eye, and in all the figures the thread on the bobbin is supposed to be wound in the usual way, shown in Figure 1, that is, from left to right it goes over, thence down under from right to left.

I will call the top of the shuttle as it runs in a loom as the "top side," and the bottom as the "bottom side."

In the drawings, Fig. 1 is a plan view of the front end of a shuttle with a metal threading block to which is attached, and in which is embodied my device.

Fig. 2 is an elevation from the left of Fig. 1.

Fig. 3 is a view similar to Fig. 2 of a threading block in which my invention is incorporated, the shuttle being indicated by dotted lines and portions of the block being shown as broken away to show more clearly the course of the thread, and the thickness

of the sheet metal parts being shown as exaggerated for clearness.

55

Fig. 4 is a section on line 4—4 of Fig. 1 looking from the left, that is, in the direction of the arrows. In this figure the thickness of the metal is somewhat exaggerated and the thread is shown as it would appear 60 after a loop has formed and is clearing itself from the hook.

Fig. 5 is a front elevation of a shuttle with my device attached.

Fig. 6 is an elevation from the side opposite that shown in Fig. 3 of a threading block in which my device is incorporated.

Fig. 7 is a front elevation and Fig. 8 a rear elevation of Fig. 6.

Fig. 9 is a section from the top on line 70 9—9 of Fig. 7.

Fig. 10 is a front elevation similar to Fig. 7 of a modification of my device.

Fig. 11 is a side elevation similar to Fig. 3 of another modification, some parts being 75 shown as exaggerated to better show the construction and principle of operation.

Fig. 12 is a back elevation similar to Fig. 8 of another modification.

Fig. 13 is a perspective view of a cast 80 blank for my threader, and Fig. 14 a back view thereof finished.

S is a shuttle having the usual bobbin chamber 10 for the bobbin B from which the thread A is unwound. 12 is the threading 85 chamber which extends forward in continuation of bobbin chamber 10, and 13 is the delivery passage which extends still farther forward from the threading chamber. H represents the shuttle eye in the wood, and 90 this connects with the threading chamber 12 through the slot 15 and the slot 14 cut away from the delivery passage 13. The usual bearing pins 17, 17 are shown.

An important feature of my device is the 95 thread directing guide plate G which, in Figs. 1 to 9, is shown as being attached to, by being set into, a threading block F.

I may attach such a sheet metal thread directing guide plate to a threading block, such 100 as F, which has at the front end a horn 32, at the bottom a projection 34 which sets into a recess in the wood of the shuttle, and a hole 35 for retaining bolt or screw 36, all in a well known manner. Such threading 105 block G is shown as having a longitudinal

passage 131 and side walls 130 and 133 which together form an interior threading chamber somewhat smaller than the threading chamber 12 in the wood.

- 5 The thread directing guide plate G preferably has a nose 19 which extends forward of the shuttle eye outlet H and at 22 slopes down and back from the nose and down and out through the threading chamber toward
- 10 the side of the shuttle away from the shuttle eye outlet H.

The top part 21 of plate G is shown as bent down to form a top rim 20 which sets into a suitable groove 37 extending lengthwise of the top 30 of threading block F. Rim 20 is preferably brazed into groove 37. Block F, which is detachably attached to the wooden part of the shuttle, may be considered a part thereof.

- 20 Near its back, the bottom edge 26, which is shown as sloping down and back from the nose 19, is bent under to form a thread retaining guide hook 24 which is shown as extending from and under the guide plate 25 up to a point back of the shuttle eye and proximate the bobbin chamber.

Directly in front of this hook 24 is an open space 25 which may continue out to the nose 19, but I prefer to bend over the bottom edge of the guide plate to form a hooked rim 27 which extends under the sloping forward part of the thread directing guide to a point in front of the shuttle eye and preferably up to the nose 19. This 35 is preferably cut away at the front and back to rake forward and back.

I prefer that my guide hook 24 should be so cut away from the rear that it will rake somewhat forward and that its front edge 40 should be formed so that the hook will narrow in whereby any loop of the thread A which may be formed will tend to slip off. By so cutting away the trapping rim and guide hook and by forming the back edge 45 125 of my guide plate to rake forward, any loops which may be formed will clear themselves, as shown in Fig. 6 and Fig. 4.

In any event, the edges of the guide parts, especially the guide plate, should be so cut 50 away that the loops will naturally clear themselves as the shuttle moves.

The back edge of 27 and front edge of 24 may be nearly parallel and at right angles with the axis of the shuttle.

- 55 The threading block F is partly of a well known form, being of somewhat triangular shape, and has a forward edge 31, which becomes part of the head or extension from horn 32 of well known type. Preferably 60 the metal at 6 extends forward curving down along slope 22 as shown in Figs. 4, 3 and 6. I also show a thread pin 33 around which the thread A passes when the shuttle is correctly threaded.

I prefer that my thread retaining hook 65 guide 24 should be so cut away from the rear that it will rake forward, as clearly shown in Fig. 4, and will taper either to a blunt or sharp point, and I prefer that my trapping rim 27 should be cut away at its 70 front and back, both for the purpose of causing loops formed by the ballooning or throwing of the thread to clear themselves.

In the operation of my device, the thread A is held in a loom beyond the front end 8 of a shuttle, and as the shuttle recedes the thread rapidly unwinds from the bobbin B, traveling in a path which may be likened to a cone which bellies to some extent. The thread flying over the sloping side of my 80 guide plate naturally follows it and slips down under and into the thread trapping rim 27, if such is used. As it is now caught in the nose or mouth at the front of rim 27, the apex of its cone of revolution is brought 85 nearer to hook 24, and the thread being trapped, so to speak, slips more easily over such hook.

This mouth 101 of rim 27 controls the ballooning or bellying of the thread, and 90 also holds it up under the top of the guide plate so that, when the shuttle stops, any loop formed by the slackening of the thread drops down into the delivery passage 13 or grooves 14 and 15 where it can do no harm. 95

Such holding up, in fact, helps it to drop into the grooves 14 and 15 on the second pick when the shuttle is returning and tends to overcome any tendency to go over to the right and unthread.

By making my guide plate G of trumpet shape with the top edge of trapping rim 27 above the bottom of mouth 101 and the curl of rim 27 and mouth 101 small, the ballooning of the thread is limited and its tendency 105 to throw or loop is greatly reduced.

Generally, during the first pick, the thread runs through the guide hook 24 and trapping rim 27, while on the second pick it slips over the cut-away front edge of rim 27 and, passing through the open part 25 of the bottom edge of guide plate G, it runs out through the shuttle eye H around the friction pin 33.

It has been proposed to form the guide 115 hook 24 of such length that it will curl back on itself under the guide plate in involute form, but I prefer to cut it off at the point indicated, shown as slightly above the horizontal, and to provide a locking guide 80 shown as attached to back end of the threading block so as to extend into the threading chamber back of and overlapping the guide hook, preferably at such a distance therefrom as to allow the thread to 120 slip around the outside of the guide plate and guide hook to the inside thereof. This locking guide does not interfere with the 125

thread getting into the guide hook but, as it overlaps the latter, it prevents the thread from flying out therefrom.

Moreover, it permits the thread to balloon in an oval with vertical axis, which is considered an advantage on some classes of work.

Preferably I also bore a hole 84 through the threading block F at such a point that 10 the top of such hole will be in front of and overlapping the guide hook. I then fill this with friction material, such as felt, 85, which will be in front of and overlapping the guide hook 24, and this, with the locking guide 80, effectually hold the thread in place after it has slipped in on the second pick.

If, on account of ballooning or for any other cause, the thread slips out of the eye 20 H and back through the passages 14 and 15, it ordinarily would be trapped by the rim 27, but if it escapes therefrom or does not enter therein, it may work back past the friction and run out through the open space 25 25, still being held by the guide hook 24 until the next throw, when it will rethread.

While I prefer to use a trapping rim 27 of hook form, I may use a rim, such as shown at 86 in Fig. 10, which extends well 30 down but is not curled up. Such a trapping rim, especially if it and nose 19 run well forward, tends to prevent the thread from unthreading between the first and second picks and to throw the thread toward the eye in the wood for threading.

I show Fig. 10 as a single complete casting.

In Fig. 11, instead of the round hole for friction material, I show a square cut 38 40 for the reception of friction material 39 shown as extending up, overlapping the guide hook.

In Fig. 12, I show a construction in which the inside edge of guide hook 24 comes in 45 fairly close to the inside wall 133 of the threading chamber. This wall is cut away at 132, and swells out at 134 so as to overlap the end of the guide hook at a point at a distance back thereof sufficient to allow 50 the threading of the shuttle.

Another distinct advantage of my shuttle threader which I claim involves invention is that it can be cast in one piece, then machined and bent into shape.

55 Such a construction I show in Figs. 13 and 14. Fig. 13 shows my shuttle threader blank as it is cast, and Fig. 14 shows the same blank when finished.

This threader consists of a single piece of 60 metal in which the threading block and guide plate, locking guide and other parts are all integral. 231 is a longitudinal threading chamber near the back of which may be cast a depression 287 in line with

and to receive guide hook 224. The locking 65 guide 286 is formed by the metal left at the back of this depression.

The trapping rim 227, guide hook 224 and the open space or runway 225, with the guide plate 222, are all cast or formed 70 flat and at substantially right angles to and integral with a high side wall 233 of the threading chamber and extend over the opposite low wall 230.

The latter must be made low enough to 75 permit the guide hook 224 to be bent with guide plate 222, as shown by the dotted lines in Fig. 14, and then over it into the position shown by the full line in Fig. 14.

The friction overlapping the guide hook 80 224 at the front may also be regarded as a locking guide therefor.

I claim:

1. The combination in a shuttle having an eye, a bobbin chamber, and a threading 85 chamber in continuation thereof which connects with the eye, of a thread directing guide plate so fixed to the top side of the shuttle as to extend into the threading chamber, such guide plate having a nose 90 which extends forward of the eye and having a bottom rim which slopes down and back from the nose and down and forward from the back through the threading chamber and at the side slopes down and out, and 95 a thread trapping rim of hooked form which extends under the sloping forward part of the thread directing guide plate, with a thread retaining hook guide which extends from and under the thread directing guide plate back of the shuttle eye and of the trapping rim, and a locking guide which extends into the threading chamber 100 back of and overlapping said hook guide, together with a friction which extends in 105 front of and overlapping said hook guide.

2. The combination in a shuttle having an eye, a bobbin chamber, and a threading chamber in continuation thereof which connects with the eye, of a thread directing 110 guide plate so fixed to the top side of the shuttle as to extend into the threading chamber, such guide plate having a nose which extends forward of the eye and having a bottom rim which slopes down and 115 back from the nose and down and forward from the back through the threading chamber and at the side slopes down and out, and a thread trapping rim of hooked form which extends under the sloping forward 120 part of the thread directing guide plate, with a thread retaining hook guide which extends from and under the thread directing guide plate back of the shuttle eye and of the trapping rim, and a locking guide 125 which extends into the threading chamber back of and overlapping said hook guide.

3. The combination in a shuttle having an

- eye, a bobbin chamber, and a threading chamber in continuation thereof which connects with the eye, of a thread directing guide plate so fixed to the top side of the shuttle as to extend into the threading chamber, such guide plate having a nose which extends forward of the eye and having a bottom rim which slopes down and back from the nose and down and forward from the back through the threading chamber and at the side slopes down and out, with a thread retaining hook guide which extends from and under the thread directing guide plate back of the shuttle eye and of the trapping rim, and a locking guide which extends into the threading chamber back of and overlapping said hook guide.
4. The combination in a shuttle having an eye, a bobbin chamber, and a threading chamber in continuation thereof which connects with the eye, of a thread directing guide plate so fixed to the top side of the shuttle as to extend into the threading chamber, such guide plate having a bottom rim which slopes down and back through the threading chamber and at the side slopes down and out, with a thread retaining hook guide which extends from and under the thread directing guide plate back of the shuttle eye, and a locking guide which extends into the threading chamber back of and overlapping the hook guide at such a distance therefrom as to allow the thread to slip around the outside and to the inside of the hook guide.
5. The combination in a shuttle having an eye, a bobbin chamber, and a threading chamber in continuation thereof which connects with the eye, of a thread directing guide plate so fixed to the top side of the shuttle as to extend into the threading chamber, such guide plate having a bottom rim which slopes down and back through the threading chamber and at the side slopes down and out, with a thread retaining hook guide which extends from and under the thread directing guide plate back of the shuttle eye, and a locking guide which extends into the threading chamber back of and overlapping the hook guide.
6. The combination in a shuttle having an eye, a bobbin chamber, and a threading chamber in continuation thereof which connects with the eye, of a thread directing guide plate so fixed to the top side of the shuttle as to extend into the threading chamber

ber, such guide plate having a bottom rim which slopes down and back through the threading chamber and at the side slopes down and out, with a thread retaining hook guide which extends from and under the thread directing guide plate back of the shuttle eye, and a locking guide which extends into the threading chamber so as to overlap the hook guide.

7. The combination in a shuttle having an eye, a bobbin chamber, and a threading chamber in continuation thereof which connects with the eye, of a thread directing guide plate so fixed to the top side of the shuttle as to extend into the threading chamber, such guide plate having a nose which extends forward of the eye and having a bottom rim which slopes down and back from the nose and down and forward at the back edge through the threading chamber and at the side slopes down and out, and a thread trapping rim of hooked form which extends under the sloping forward part of the thread directing guide plate.

8. A shuttle threader having a longitudinal threading chamber and a thread directing guide plate which extends from the top into such threading chamber, said guide plate having a bottom rim which slopes down and back through the threading chamber and at the side slopes down and out, a thread trapping rim of hook form which extends from and under the sloping forward part of the thread directing guide plate, a thread retaining guide hook which extends from and under the thread directing guide plate back of the thread trapping rim, and a locking guide which extends into the threading chamber so as to overlap the hook guide.

9. A shuttle threader having a longitudinal threading chamber and a thread directing guide plate which extends from the top into such threading chamber, said guide plate having a bottom rim which slopes down and back through the threading chamber and at the side slopes down and out, a thread retaining guide hook which extends from and under the back part of the thread directing guide plate, and a locking guide which extends into the threading chamber so as to overlap the hook guide.

In testimony whereof I have affixed my signature.

ISAAC SNOW.
